HERMAN E. WENDELL, OF ST. PETERSBURG, FLORIDA, ASSIGNOR OF ONE-THIRD TO PAUL HORNLEIN, OF ST. PETERSBURG, FLORIDA, AND ONE-THIRD TO DUNCAN M. MOODIE, OF MELROSE, MASSACHUSETTS

CRATE

Application filed March 9, 1932. Serial No. 597,816.

My invention relates to improvements in crates of the type used particularly for citrus fruits, such as grapefruit, oranges, etc., and it consists in the constructions, combination, 5 and arrangement of parts herein described and claimed.

In the manufacture of crates for shipping citrus fruits and the like, the makers of these crates proceed according to certain prescribed 10 rules relating to sizes, shapes, material, ventilation, etc., so as to secure a uniform standard. In making the ordinary crate there are numerous operations and many parts. The 15 nailing of the crates in itself takes considerable time and as each separate operation adds to the time it also adds to the cost of the crate. The fact that there are so many parts in the ordinary crate and that these parts have to all be handled separately, 20 makes the manufacture of a crate more complex than one would ordinarily think.

An object of my invention is to provide a crate which is made without the use of nails or staples and which consists of a minimum 25 number of parts.

A further object of the invention is to provide a crate having metal end portions and means carried by these end portions for not only securing the ends of wooden side 30 members thereto but for holding them in spaced relation.

A still further object of the invention is to provide a box having a minimum of parts which can be assembled with a minimum 35 number of operations, thus resulting in a box which can be manufactured cheaply.

My invention is illustrated in the accompanying drawing forming part of this application, in which:—

40 Figure 1 is a perspective view of a completed crate,

Figure 2 is a transverse vertical section, and

Figure 3 is a horizontal section.

45 In carrying out my invention I provide metal end portions such as those shown in the drawing. These metal end portions are similar in construction and a description of one will suffice for both. In the drawing I 50 have shown a rectangular body portion 4

formed of sheet metal. This body portion has integral flanges 5, 6, 7 and 8 which are bent at right angles to the body portion, then outwardly, and then back again, thus providing a U-shaped groove along each edge 55 of the body portion.

The side members are wooden slats. The drawing shows a box of a half bushel capacity with two slats 10 and 11 on one side and two slats 12 and 13 on the opposite side with 60 slats 14 and 15 disposed at right angles thereto.

The ends of the slats are received in the grooves 9, the slats 10—11 and 12—13 being spaced apart from one another. As shown in 65 the drawing, the lower edges of the wooden side members or slats are also received in the grooves of a companion metal end member.

After the wooden side members have been 70 assembled the metal end members are placed in machines and then the flanges are crimped, as shown at 16; that is to say, they are bent over the edges of the adjacent wooden side members. The ends of the flanges are turned 75 inwardly at 17. As will be seen from Figure 3, these turned-in portions 17 are on the opposite edges of the slats from the crimped portions 16 and they are also at the ends of the slats 14 and 15. Thus the slats are held 80 firmly in position while the portion 16 acts as a spacer between the side slats 10—11 and 12—13.

It will thus be seen that the making of the 85 crate is very simple. In fact, as disclosed, there are only eight parts. In the standard half bushel crate there are approximately one hundred separate parts. I am aware that crates made of metal end pieces having flanges provided with grooves for receiving 90 wooden side members are not broadly new, but I am not aware of any such crates which are provided with crimped portions such as those shown at 16 which serve the double purpose of a spacer for the slats and a means 95 for retaining the slats in position without nailing or otherwise securing them.

It will be noted that any one flange and the 100 U-shaped groove formed thereby terminates short of the adjacent flange. Furthermore,

the ends of the flanges are slightly bevelled away from each other.

- A box may be made as described without, however, crimping the ends 17 of the flanges 5 on one face of the box. This provides means for covering the box when it is filled with fruit. All that is necessary is to slip one slat into the groove 9 from one end of the flange until it engages the central crimp 16 and to 10 slip another slat in from the other end and then turn inwardly or crimp the ends over the outer edges of the slats by machine or by a hand tool, thus holding the cover securely in position.
- 15 In opening the box all that is necessary is to bend back the crimped portion 17 on one face of the box and then to move the slats outwardly, thus exposing the contents.

I claim:—

- 20 A crate comprising a pair of rectangular metal end pieces, said end pieces having integral U-shaped flanges to provide grooves, the grooves of one end piece facing the other, wooden side members having their ends disposed in the grooves of said end members, said flanges being crimped to provide a spacing means between certain of said side members, the ends of said flanges being bent inwardly over the edges of the contiguous 25 wooden side members, thereby holding said side members securely.
- 30
